UNITED STATES PATENT OFFICE

2,518,261

A SHOE TREE

Howard C. Vining, Brockton, Mass., assignor to
 Jay-Vee Shoe Tree Company, Brockton, Mass.,
 a corporation of Massachusetts

Application December 7, 1948, Serial No. 64,025

1 Claim. (Cl. 12—128.6)

1

The present invention is a novel and improved shoe tree or display form, wherein a full support is imparted to the vamp or forepart of a shoe when fitted therein, and incorporates a special line of cut and novel position for the connecting link between the forepart and heel part of the tree or form.

Heretofore in devices of this type wherein a full support is desired for the forepart, with adjustments for length between forepart and heel part of such a form as, for example, shown in my prior and co-pending application Ser. No. 766,281, filed August 5, 1947, which has matured into United States Patent 2,503,227, granted April 4, 1950, the shoe tree construction provided for a considerable opening in the line of cut between the front or cone portion of the forepart and heel part, which opening failed to provide a full support to the forepart.

Furthermore, the line of cut and the flexing of the tree or form when being fitted into a shoe was liable to catch the upper part of the vamp and particularly the shoe lace, which thus would mar the appearance of the shoe displayed on such a form. As these shoe trees and forms are very largely intended to maintain the shoe upper in smooth, efficient, and attractive contour and eliminate wrinkles, or the like, and thus present an attractive appearance as well as an efficient support for the upper of the shoe, the former construction was unsatisfactory in many respects.

I have discovered that by forming a special line of cut on a predetermined bevel or angle between the forepart and heel part, together with the novel position of the connecting link or hinge element, that prior difficulties and objections to a shoe tree or display form of this general type were eliminated.

Furthermore, an important advantage of my present invention is that the heel part of the form when flexed or rocked on its pivot will quickly and instantly shorten the last in its lengthwise relationship to the shoe in which it is fitted and, thus, will permit the form to be applied to or withdrawn from a shoe without undue strain during this operation.

Heretofore most lasts as well as shoe forms and shoe trees of this general type have had a hinge element, or elements, positioned in proximity to the bottom of the last and in the general line of pressure from the toe to the heel. Such a construction, however, after the two last members had been adjusted for length required the forcing of the heel part into the counter of the shoe to which the last was being fitted, and tended

to unduly strain the upper, stitching, and style and model of the shoe. A similar undue straining was caused when the shoe tree was withdrawn.

5 In my present invention I have eliminated these prior difficulties and by means of my novel location of the hinge element and its fastening in proximate position to the front or cone of both forepart and heel part, I am enabled to secure a very quick longitudinal shortening of the form 10 when being withdrawn from a shoe, as well as a quick lengthening when being applied, without unduly straining the shoe counter, wrinkling the vamp, distorting the style or model, or otherwise 15 damaging the shoe to which the form is fitted.

Thus, important features of my present invention consist in the angle of cut between forepart and heel part, the position in which the 20 connecting link and its fastenings are proximate to the front or cone of the last rather than to the last bottom, and the maintenance of a full support to the forepart of the vamp, with the top edge of the vamp covering the space between the 25 forepart and heel part, thus giving full support and a better appearance to a shoe fitted on my improved tree or form, as well as eliminating catching of the shoe lace during the flexing or shortening operation, while still permitting relative longitudinal adjustment between the forepart and heel part.

The shoe tree is turned in any standard turning lathe and, thereupon, divide the same into a 30 cooperating forepart and heel part on a line of cut at an angle extending from the bottom upwardly so that the top opening will be within the area of a shoe vamp with which the display form is intended to be used. Thus this line of 35 cut permits the shoe vamp to extend from the space normally required between the forepart and heel part for longitudinal adjustment, and enables the vamp to rest upon the front portion of the forepart, thus covering the space between the two parts and insuring protection against catching 40 and damage to the shoe lace, as well as support to the top frame of the vamp of the shoe. This is an important feature, as will be further explained.

Referring to the drawings illustrating a preferred embodiment of my present invention:

Fig. 1 is a side view of a display form showing the dotted outline of a shoe to be fitted thereon; and

Fig. 2 is a view partly in cross-section showing 55 the last in flexed position in the process of being

inserted in or withdrawn from the shoe in which it is fitted.

As shown in the drawing, the last comprises a forepart 1 and heel part 2 divided on a straight line of cut as indicated at 3 on the forepart and 4 on the heel part. This line of cut is on an angle slantingly inclined from the last bottom upwardly to the front portion of the last parts in a position more nearly adjacent the forepart or toe portion of the last than has heretofore been customary. Thus the opening of the side walls 3 and 4 on this slanting line of cut will be at a point in the front of the last below the top of a shoe to be fitted thereon. A typical shoe outline is illustrated in dotted lines at 10. In order to unite the forepart and heel part on a line of linkage which will insure the quick shortening of the last form when being flexed and, hence, quick withdrawal of the heel part 6 from within the counter or heel portion of the shoe, as indicated at 8 in the dotted outline, the connecting linkage element is fitted to the heel part and forepart at points adjacent the front line of the form, as shown.

I also prefer to have this link element adjustable to allow a range of adjustment between the forepart and heel part to fit shoes of different lengths and sizes. For this purpose I provide a link or hinge member 12 having one end flattened, as shown at 13, to fit within a narrow soft kerf 14, here illustrated as made in the forepart, and held in position by a pin 15. The opposite end portion of the link 12 is threaded, as shown at 18, and is threaded into a bored opening 20 in the heel part in alignment with the pivot 15 of the forepart so that when the last form or shoe tree is in extended position within the shoe, the line of curvature and contour of the forepart and heel part will be in correct alignment to support the front of the shoe 10, thus giving a smooth and attractive display feature on the shoe and also eliminate any danger of the shoe lace being caught within the opening between the two parts. A handle 21 may be added, if desired, for convenience in inserting the display form and removing it from a shoe in which it may be fitted.

It will thus be appreciated that my present novel design and construction of a display form, shoe tree, follower, or similar last insures a full support to the forepart of a shoe, free of the danger of catching the shoe laces, permits a quick shortening of the last lengthwise when the heel part is raised on the pivot 15, thus preventing danger of straining the heel part of the shoe during the removal from or fitting in of the display form, and also providing a novel line of cut between the forepart and heel part which facilitates this quick shortening action in cooperation with the position of the connecting link or hinge.

15 I claim:

A shoe tree or display form of the kind described comprising a forepart and a heel part divided on a straight line plane, said plane extending from the bottom forwardly and upwardly at a predetermined angle into the forepart below the top thereof, whereby the heel part constitutes a support for the top of the vamp, in combination with a single link element connecting said two parts, said link having a flat portion 25 extending into and pivoted into the forepart, and a threaded portion extending into the heel part substantially on a line parallel with the front vamp-supporting portion of both parts when the last is in extended position, said heel 30 part of the link being threaded to provide longitudinal adjustment between the forepart and heel part.

HOWARD C. VINING.
